UNITED STATES PATENT OFFICE.

ROBERT HOSKIN, OF NEW YORK, N. Y., ASSIGNOR TO C. M. BAILEY, OF SAME PLACE.

DESIGN FOR CARPET.

Specification forming part of Design No. 6,521, dated March 25, 1873.

To all whom it may concern:

Be it known that I, ROBERT HOSKIN, of the city, county, and State of New York, have invented a new and original Design for Carpets, of which the following is a specification:

The nature of my invention is fully represented in the accompanying photographic illustration, to which reference is made. This invention relates to a new carpet-design, which embraces a new hexagonal diamond-shaped center-piece arranged on a plain background.

The diamond-shaped figure is composed of a square center embracing an octagon, rectangular side extensions, suitably connected by triangular pieces, completing the hexagon. Diagonal spurs project toward the corners of the surrounding rectangle, the inner side of

which is provided with triangular spurs. The outer side is even, the body of the rectangle being appropriately mottled. The longitudinal sides of the rectangle extend over the carpet, and similar sides branching off at right angles near the corners.

I claim as my invention—

The design herein described, consisting of the mottled rectangle, with inside projecting spurs embracing a hexagonal center-piece having diagonal spurs, and consisting of a square center surrounded by rectangular extensions and triangular connections, as shown.

ROBERT HOSKIN.
